UNITED STATES PATENT OFFICE.

GEORGE H. TAYLOR, OF NEW YORK, N. Y., ASSIGNOR TO THE KURSHEEDT MANUFACTURING COMPANY, OF SAME PLACE.

DESIGN FOR FABRIC.

SPECIFICATION forming part of Design No. 33,728, dated December 11, 1900.

Application filed October 30, 1900. Serial No. 34,955. Term of patent 14 years.

To all whom it may concern:

Be it known that I, GEORGE H. TAYLOR, a citizen of the United States, residing in the borough of Manhattan, city, county, and State of New York, have invented and produced a new and useful Design for Fabric, of which the following is a specification.

My design consists of fabric of essentially the configuration and representation shown in the accompanying drawings.

In the drawings, Figure 1 is a face view of a piece of fabric in which my design is embodied. Fig. 2 is a section on line 2 2 of Fig. 1, and Fig. 3 is a section of Fig. 1 at right angles to the line 2 2.

The leading feature of my design is fabric having undulating flutes or plaits, the said plaits likewise having alternated undulations

and depressions, the undulations and depressions of adjacent plaits being in line with each other.

In the drawings, *a* is the fabric having the undulated flutes or plaits *b*, which undulated flutes or plaits *b* have the alternating elevations *c* and depressions *d*, the depressions *d* of adjacent plaits being in line with each other and the elevation *c* of adjacent plaits also in line with each other.

What I claim is—

The design for fabric substantially as herein shown and described.

GEORGE H. TAYLOR.
